UNITED STATES PATENT OFFICE.

CARL OTTO, OF BOCHUM, GERMANY.

VERTICAL-CHAMBER OVEN.

Application filed February 5, 1925. Serial No. 6,892.

My invention relates to a vertical coke oven with one or more vertical coking chambers and particularly to such ovens as are provided with regenerators at both of the 5 front faces of the chambers.

One of the objects of my invention is to provide a vertical coke oven with means for preheating the air supplied for combustion at each front of the oven at the same 10 time providing a corridor for feeding the burning gases from one oven wall of the pair that heats the oven chamber, to another heating wall, in particular to the other heating wall of the pair, and then discharging the products of combustion at the other oven face opposite to the face where the combustion flame was fed in.

More particularly speaking, another of the objects of my invention is to provide 20 regenerators at one front face of the oven chambers for supplying preheated gas and air to the associated heating walls and then to feed the burning gases from the said heating walls to other heating walls on the 25 other side of the oven chambers, the products of combustion being thereupon delivered to regenerators arranged at the other front face of the oven chambers. The flues of two heating walls are connected so as 30 to form a separate heating system. At suitable intervals the oven is reversed. The regenerators which have previously received the products of combustion, or waste heat, serve, on reversal, to preheat the gas and 35 air and the preheating regenerators at the other oven front, serving to receive the discharged products of combustion. The burning gases, on reversal of the oven, pass in the reverse direction from one heating wall 40 to the other.

In accordance with the invention, the products of combustion are fed from one heating wall to another heating wall so that only one half of the regenerator chambers 45 and one half of the reversing mechanism are needed. Moreover, by this construction the leaking surfaces between the air and the gas regenerators are much reduced, which very much increases the safety of operation. 50 Again, my invention provides regenerator spaces of such a width that they can be easily entered, upon removal of a few stones from their faces.

With the above and other objects in view, 55 my invention consists in the parts, improve-

ments and combinations more fully pointed out hereinafter.

Referring now to the drawings:

Figure 1 is a vertical sectional view on the line 1—1 of Figure 3. 60

Figure 2 is a horizontal cross-section on the line 2—2 of Figure 1.

Figure 3 is a horizontal cross-section on the line 3—3 of Figure 1.

Figure 4 is a vertical sectional view of 65 a modification of the invention,

Figure 5 is a vertical cross-section on the line 5—5 of Figure 4 and,

Figure 6 is a vertical sectional view of 70 another form of the invention.

In the drawings two forms of the invention are shown in which the heating walls are provided with vertical heating flues. Horizontal heating flues may be employed.

The regenerators 1 and 2, are arranged 75 at one front of the oven in front face of the narrow sides of the oven chambers 3. Regenerators 1 are provided for preheating the gas and regenerators 2, are provided for preheating the air. The air regenerators 2, are arranged side by side and the gas regenerators 1, are also arranged side by side, thus reducing the danger of leakage between the air regenerators and the gas regenerators. Gas from gas supply main 4 85 and air from airpipe 5, go to the respective regenerators 1 and 2. In the form of the invention illustrated, the gas main 4, may feed each of the regenerators thru connecting pipes 6, 7, and a series of air pipes 5, 90 may be used, one for each gas pipe connection. In order to supply air to one set of regenerators and gas to another set, alternate air valves and intermediate gas valves are opened, the remaining air and gas valves 95 being closed. From these regenerators, the gas and air enter at the bottom of the corresponding heating wall 8, thru passageways 9, 10, where, after entry, they unite for the purpose of combustion. This mixing can take place as shown in the drawing, at one place for each heating wall, or air and gas can be separately fed to the heating walls from the regenerators by means of two horizontal flues arranged at 100 the lower part of the heating wall, and fed therefrom to each heating flue.

From the heating wall 8, the burning gas or products of combustion will then pass thru corridors 11, to another heating wall 12, 110

- two corridors being preferably used, one at each front face. This heating wall in the best embodiment of the invention, is the other heating wall of the oven chamber. After 5 passing down the heating flues of the latter heating wall, the products of combustion will pass into the regenerators 13, 14, located at the other front face of the oven by way of passageways 15, 15^a. After the 10 gases have passed thru the regenerators they will pass out of the oven thru pipe 16 and stackflue 17. The valve 18, will then be open and the air valve 19, and gas valve 20, will be closed.
- 15 By reversal of the regenerators, the reverse operation takes place. Air being admitted thru airpipe 19, valve 18, being closed, and gas being admitted from gaspipe 21, the adjacent valve 20, being open, thru 20 connecting pipes 22, 23, the air and gas for combustion will pass from the regenerators 13, 14, into the heating flues of the heating walls 12, and from these thru the transfer corridors 11, into the heating flues of the 25 heating walls 8, and from here into the regenerators 1 and 2, and out by way of pipe 24, to stackflue 25, valve 26 being then open, and air valve 5, and gas valve 28, being then closed.
- 30 The division walls forming the flues are preferably made of unequal length so as to leave the largest opening for the flame flow nearest to the inlet and providing decreasing cross-sectional areas for the flame as it 35 proceeds toward the other end of the heating wall. This is shown in full lines in Figure 1. On the other side of the oven chambers the reverse construction is employed; the division walls of the heating flues increase in length at their lower ends, as shown 40 by the dotted lines in Figure 1, the walls being shortest and the opening largest where the flame enters, when the heat is reversed. The walls become longer where the flame 45 reaches the end of the heating wall.
- In the modification shown in Figures 4 and 5, the corridors 29, 30, which connect one heating wall to the other pass over the tops of the oven chambers.
- 50 Observation passages 31, 32, 33, 34, 35, 36, closed by plugs 37, 38, 39, 40, 41, 42, (Figure 1), are provided permitting inspection of the oven flues and corridors upon removal of the plugs.
- 55 In the preceding description the oven has been described as heated by weak gas. When heated by strong gas, this may be supplied thru pipes 43, 44. Waste heat is then supplied from the mains 4 and 21 and air is supplied thru airpipes 19 and 5.
- 60 The above described means of heating with the feeding in of gas and air below the heating wall is particularly useful for oven chambers operated discontinuously, i. e. in which 65 the coal is supplied to the oven chamber

after each coking operation. When the oven chamber is fed continuously with coal, air and gas are supplied from the respective regenerators to the corresponding heating wall for combustion and the transfer of the 70 products of combustion from one wall to the other is provided for by connecting the corridors at the bottom of the heating walls (see Figure 6).

Figure 6, illustrates a vertical chambered 75 oven in which coal may be fed continuously to the top of the oven chambers by any suitable means (not shown). The coal enters at the tops of the oven chambers and entering cold, it is necessary to supply the greatest heat at the top so as to heat it quickly. Gas mains 45, 46, supply gas as in the preceding figures and air pipes 47, 48, are provided as before, together with stackflues 49, 50, and reversing valves 51, 52. The gas and air enter at the bottom of the respective regenerators 53, and rise thru them, being ignited at the tops of the combustion flues and passing downwardly thru them. The flame then passes to the next heating wall on the 90 other side of the oven chambers thru corridors 55, 56, pass up thru the heating flues of the other heating wall, discharges into regenerators 54, at the top, goes down thru the regenerators 54, and discharges at the bottom of the regenerators into stackflue 50. The oven is reversed at intervals by operation of the reversing valves 51, 52, and gas valves 58, 59, with the corresponding air-valves of pipes 47, 48, the products of combustion discharging thru stackflue 49.

In order to obtain, in the regenerators for preheating the air and the gas, a uniform travel, the regenerators are provided with baffle plates so located that this operation will occur. This can also be brought about by providing connecting passageways connecting the upper part of the regenerators with the lower part of the corresponding heating wall.

When gas preheating is not required, the gas preheating regenerators may be omitted.

Having thus described the invention and its operation, it will be understood that changes may be made in carrying the invention into effect, without departing from the principle of the invention.

What I claim is:

1. In a vertical horizontally elongated chamber coke oven the combination with 120 the vertical oven chamber having heating walls at the sides of said chamber, each heating wall provided with a series of flues, means for so connecting the flues of one heating wall with the flues of another heating wall of the said oven chamber that the burning gases may pass from the flues of one heating wall to the flues of another heating wall, and means at each front face of the oven, in front of the narrow sides of 125 130

- the oven chambers for preheating the air supplied to the flues of each heating wall.
2. In a vertical chamber coke oven the combination with the vertical oven chambers having heating walls at the sides of said chambers, each heating wall provided with a series of flues, means for so connecting the flues of one heating wall with the flues of another heating wall of the oven chambers 10 that the burning gases may pass from the flues of one heating wall to the flues of another heating wall, and regenerators at each front face of the oven for preheating the air supplied to the flues.
- 15 3. In a vertical chamber coke oven the combination with the vertical oven chamber, having heating walls at the sides of said chamber, each heating wall provided with a series of flues, means for so connecting the flues of one heating wall with the flues of another heating wall of the said oven chamber that the burning gases may pass from the flues of one heating wall to the flues of another heating wall, and a pair of 20 regenerators at each front face of the chamber, one for preheating the air and the other for preheating the gas supplied to the flues.
4. In a vertical chamber coke oven the combination with a plurality of vertical oven chambers, arranged in a row, having heating walls at the sides of each chamber, each heating wall provided with a series of flues, means for connecting the flues of one 30 heating wall with the flues of another heating wall of said oven chambers so as to form separate heating systems and so that the burning gases may pass from the flues of one heating wall to the flues of another heating wall, and a plurality of regenerators at each front face of the oven for preheating the air supplied to the flues, there being a separate air regenerator for each 40 separate heating system, in each front face.
- 45 5. In a vertical chamber coke oven, the combination with the vertical oven chamber, having heating walls at the sides of said chamber, each heating wall provided with a series of flues, a corridor for connecting the tops of the flues of one heating wall with the tops of the flues of another heating wall of said oven chamber so that the burning gases may pass from the flues of one heating wall to the flues of another heating wall, and means at each front face of the chamber, for preheating the air supplied to the flues.
- 60 6. In a vertical chamber coke oven the combination with the vertical oven chamber, having heating walls at the sides of said chamber, each heating wall provided with a series of flues, a pair of corridors for connecting the tops of the flues of each heating wall to the tops of the flues of another heating wall so that the burning gases may pass

from the flues of one heating wall to the flues of another heating wall, and regenerators at each front of the chamber for preheating the air supplied to the flues.

7. A vertical chamber oven provided with 70 vertical oven chambers and with regenerators located at each front of the oven for preheating gas and air, said oven chambers provided with heating walls at the sides of the oven chamber, each of said heating walls 75 provided with a series of heating flues, corridors for so connecting the heating flues of two of said heating walls that the burning gases may pass from the flues of one heating wall to the flues of another heating wall, 80 means for connecting the regenerators located at one front of the oven to the heating flues of the associated heating wall, and means for connecting the flues of the other heating wall to the regenerators located at 85 the other front of the oven, the burning gas thus heating one heating wall and the products of combustion passing to another heating wall by means of said corridors and finally passing into the regenerators at the 90 other oven front.

8. In a vertical chamber coke oven the combination with the vertical oven chamber, having heating walls at the sides of said chamber, each heating wall provided with a 95 series of vertical flues, means for so connecting the flues of one heating wall with the flues of another heating wall of the said oven chamber that the burning gases may pass from the flues of one heating wall to 100 the flues of another heating wall, and a plurality of regenerators at each front of the oven, two for each connected flue system, for supplying preheated air to the flues at each front of the oven.

9. In a vertical chamber coke oven the combination with the vertical oven chamber, having heating walls at the sides of said chamber, each heating wall provided with a series of flues, means for so connecting the 110 flues of one heating wall with the flues of another heating wall of the said oven chamber that the burning gases may pass from the flues of one heating wall to the flues of another heating wall, means for supplying 115 preheated air to the flues at each front of the oven and means for discharging the products of combustion at each front of the oven.

10. In a vertical chamber coke oven, the combination with the vertical oven chambers, having heating walls at the sides of said chambers, each heating wall provided with a series of flues, means for connecting the flues of one heating wall with the flues of another heating wall of the said oven chambers 120 so as to form separate heating systems, and so that the burning gases may pass from the flues of one heating wall to the flues of another heating wall, and means for supplying preheated air to the flues at the alter- 125 130

- nate fronts of the heating walls at each front face of the oven.
11. In a vertical chamber coke oven the combination with the vertical oven chambers, having heating walls at the sides of each of said chambers, each heating wall provided with a series of flues, means for so connecting the flues of each heating wall of an oven chamber with the flues of another heating wall of the said oven chamber, that the burning gases may pass from the flues of one heating wall to the flues of another heating wall, a plurality of regenerators one for each connected flue system for supplying preheated air to the flues at the alternate fronts of the heating walls at one front face of the oven and a plurality of regenerators one for each connected flue system for discharging the products of combustion at the alternate fronts of the other heating walls of the oven.
12. In a vertical chamber coke oven the combination with the vertical oven chambers, having heating walls at the sides of each of said chambers, each heating wall provided with a series of flues, means for so connecting the flues of one heating wall with the flues of another heating wall of the said oven chambers that the burning gases may pass from the flues of one heating wall to the flues of another heating wall, means for supplying preheated air to the flues at the alternate fronts of the heating walls at one front face of the oven, means for discharging the products of combustion at the alternate fronts of the other heating walls of the oven, and means for reversing said oven.
13. In a vertical chamber coke oven the combination with the vertical oven chamber, having heating walls at the sides of said chamber, each heating wall provided with a series of vertical flues, a pair of corridors, one at each front face of the oven for connecting the flues of one heating wall with the flues of another heating wall so that the burning gases may pass from the flues of one heating wall to the flues of another heating wall, and regenerators at each oven front for alternately preheating the air supplied to the flues of each heating wall.
14. In a vertical chamber coke oven the combination with the vertical oven chambers, having heating walls at the sides of said chambers, with intake ends, each heating wall provided with a series of vertical flues, said flues being of varying length and shortest at the intake end of the wall, means for so connecting the flues of one heating wall with the flues of another heating wall of the oven chambers that the burning gases may pass from the flues of one heating wall to the flues of another heating wall, and regenerators at each front face of the oven for preheating the air, supplied to the flues.
15. In a vertical chamber coke oven the combination with a plurality of vertical oven chambers, having heating walls at the sides of said chambers, each heating wall provided with a series of flues, means for so connecting the flues of one heating wall with the flues of another heating wall of the said oven chambers that the burning gases may pass from the flues of one heating wall to the flues of another heating wall, and pairs of regenerators at each front face of the chamber, one of the pair for preheating the air and the other for preheating the gas supplied to the flues, the gas regenerators of successive pairs being side by side and the air regenerators being likewise side by side.

In witness whereof, I have signed my name to this specification.

CARL OTTO.
